UNITED STATES PATENT OFFICE.

DONALD S. BARRY, OF CEDAR RAPIDS, IOWA.

LOADER.

Application filed November 18, 1925. Serial No. 69,515.

This invention relates to apparatus for use in preparing loads of lumber or other material such as brick, tile, bags of cement, and the like whereby the loads can be positioned readily on trucks without requiring the tedious and expensive handling heretofore necessary.

It is the practice generally to pile the material in a truck body after it has reached the point of loading and the time required to place the load on a truck has added considerably to the cost to the consumer or user.

The present invention provides a means whereby, while the truck is delivering one load of material, another load can be prepared and quickly transferred to the truck when brought to position to receive the load.

A further object is to provide for this purpose a mechanism which is simple, compact and efficient and can be readily carried from place to place so that it is thus rendered particularly suitable in lumber yards and other places where materials are stored.

A still further object is to provide a loader which can be constructed readily from standard pipes and fittings.

With the foregoing and other objects in view which will appear as the description proceeds, the invention resides in the combination and arrangement of parts and in the details of construction hereinafter described and claimed, it being understood that changes in the precise embodiment of the invention herein disclosed may be made within the scope of what is claimed without departing from the spirit of the invention.

In the accompanying drawings the preferred form of the invention has been shown.

In said drawings:

Figure 1 is a side elevation showing the loader in use, the position of one of the trestles during the transfer of the load to the truck, being indicated by broken lines.

Figure 2 is a front elevation of one of the trestles.

Figure 3 is a front elevation of another trestle forming a part of the apparatus.

Figure 4 is an enlarged section through one of the legs of the trestle, said section being taken on the line 4—4 Figure 3.

Figure 5 is an enlarged side elevation of a portion of one of the trestles showing a clamp used for connecting the cross bar to one of the legs.

Figure 6 is an enlarged side elevation of a

portion of a truck showing the roller and its pawl and ratchet mechanism.

Referring to the figures by characters of reference 1 designates a cross bar connected at its ends by elbows 2 to legs 3. A T-fitting 4 is mounted for rotation on the bar 1 close to each of the elbows 2 and extending from each of these T-fittings is a leg 5. Bar 1 and the legs 3 and 5 are preferably formed of pipes of standard sizes and the fittings used for connecting them are standard ones. Obviously the legs 5 can be swung to position between the legs 3 so that the trestle formed by these legs and bar 1 can thus lie flat upon the ground or be readily stored wherever desired. In use, however, the legs 5 can be swung relative to the legs 3 so as to assume a position approximating that disclosed at the left of Figure 1.

In connection with the trestle just described another trestle is employed, the same being illustrated in detail in Figures 3 and 4 and being shown at the right of Figure 1. This trestle includes a cross bar 6 having elbows 7 at the ends thereof to which are connected legs 8, as shown. A T-fitting 9 is mounted for rotation on the bar 6 close to each elbow 7 and extending from the T-fittings are struts 10 the lower ends of which are provided with T-fittings 11 mounted for rotation on a cross bar 12. At the ends of the cross bar are provided T-fittings 13 through which are extended legs 14. These legs are shorter than the legs 8 and have clamps 15 at their upper ends to which are connected the ends of a cross bar 16. The fittings 13 are held against sliding movement on the legs 14 by pins 17 which are extended diametrically therethrough and through the legs, there being a series of apertures 18 within the legs 14 any one of which is designed to receive the pins. Obviously by removing the pins 17 the fittings 13 can be adjusted longitudinally along the legs 14 and held at any point desired by reinserting the pins. Hooks or other suitable fastening means indicated generally at 19 are carried by the struts 10 and are adapted to engage the cross bar 16 so as to hold said bar against movement relative to the struts.

In using this apparatus the two trestles are set up with the bar 16 engaged by the fastening means 19 and the legs of the two trestles are adjusted so as to support the bars 1 and 6 at proper elevations. The material

to be loaded in a truck is piled compactly on these bars 1 and 6 as shown at M in Figure 1. The truck, a portion of which has been shown at T is provided with a roll R at its rear end, 5 retrograde movement of the roll being prevented by a pawl P and ratchet R'. This arrangement of a roll with a pawl and ratchet is an old one found upon many trucks already in use. The load on the trestles is 10 supported at such a height that when said end of the truck is brought close to the bar 6, a portion of the load overhangs the truck body. Bar 16 is then unfastened from the struts 10 and pulled outwardly as shown by 15 broken lines in Figure 1. Thus that end portion of the load supported by the right hand trestle is lowered onto the roll R. The right hand trestle is then removed from under the load and the truck is backed further 20 until it approaches the remaining trestle. At this time more than one-half the load is located upon or above the truck body and the said remaining trestle can be removed by pulling the legs 3 and 5 apart. Consequently 25 the entire load will thus be left in position on the truck. The positioning of the load can be facilitated by using a roller r which will travel forwardly between the front portion of the load and the top surface of the 30 truck body, as will be obvious.

What is claimed is:

1. In loading apparatus a trestle including a load supporting cross bar, legs supporting the same, struts pivotally connected to the 35 cross bar, legs hingedly connected between their ends to the struts, and cooperating means upon the struts and the hinged legs for holding said legs against movement relative to the struts.
- 40 2. In a loading apparatus a load supporting cross bar, legs supporting the same, struts mounted to swing relative to the legs,

legs pivotally and slidably connected to the struts, means for holding said legs against sliding movement relative to the struts and means for holding said legs against pivotal movement relative to the struts. 45

3. In a loading apparatus a load supporting bar, supporting means therefor, struts mounted to swing relative to said supporting means, supports for the struts pivotally and adjustably connected thereto, and means for holding said struts and their supports against relative swinging movement. 50

4. In a loading apparatus the combination 55 with a foldable trestle including a load supporting bar, of a second foldable trestle including a load supporting bar, supporting means therefor, struts mounted to swing relative to said bar, legs adjustable longitudinally and pivoted relative to the struts, and means for holding said adjustable legs against swinging movement relative to the struts. 60

5. In a loading apparatus a load supporting bar, supports therefor, struts mounted to swing relative to the supports, a second cross bar, legs connected thereto, said bar and legs being connected to the struts and the legs being mounted to swing relative to the struts, and means for holding said legs and struts against relative swinging movement. 65

6. In a loading apparatus a load supporting bar, supports therefor, legs, upper and lower bars connecting the legs, struts connecting the load supporting bar and the lower bar, said legs being adjustable longitudinally relative to the lower bar, and cooperating means upon the struts and the upper bar for holding the legs and struts against 70 relative swinging movement. 75

In testimony that I claim the foregoing as my own, I have hereto affixed my signature.

DONALD S. BARRY.
